(57) **CLAIM**

The ornamental design for a lighting fixture, as shown and described.

DESCRIPTION

FIG. 1 is a top plan view of the lighting fixture according to our new design, with the cords broken away to indicate indeterminate length;

FIG. 2 is a bottom plan view thereof.

FIG. 3 is a side elevational view thereof with the fixture facing downward, the other side view being a mirror image.

FIG. 4 is a perspective view thereof, looking down toward the bottom right side of FIG. 1; and,

FIG. 5 is a perspective view thereof, looking down toward the top right side of FIG. 2.

The end surfaces of the fixture are plain and non-ornamental.
